BOX CAP

Archie L. Dickson, Jr., Gulfport, Miss.

Application June 14, 1949, Serial No. 98,909

2 Claims. (Cl. 229—7)

1

This invention relates to a box cap and more particularly to a replaceable and removable cap or closure member for cardboard boxes and the like.

It is an object of this invention to provide a box top for cardboard boxes or the like for closing the box when the covers or top walls have been torn or severed therefrom. At the present time certain advertising media is printed on the top walls of cardboard containers of household material as breakfast cereal, baking powder, soap and other materials with the intent being that the purchaser shall remove the cover and return it to the manufacturer as a premium or the like. By severing the top from the containers the material within is subject to be spilled or dried and therefore it is a principal object of this invention to provide a box cap for closing such boxes after the tops have been removed and may be used on other boxes when the contents of the first box have been exhausted.

Another object of this invention is to provide a box cap of the kind to be more particularly described hereinafter which may be made of metal, plastic or other suitable material to fit on cardboard boxes with the top removed to preserve the freshness of the contents, protect the contents from dirt, bugs and the like and provide a handy method of dispensing the contents when and as desired.

With the above and other objects in view, my invention consists in the arrangement, combination and details of construction disclosed in the drawings and specification and then more particularly pointed out in the appended claims.

In the drawings:

Figure 1 is a top plan view of a box cap, constructed according to an embodiment of this invention.

Figure 2 is a side elevation of the box cap secured on a cardboard box, the cardboard box being shown partly broken away and partly in section.

Figure 3 is a transverse section, taken on the line 3—3 of Figure 1.

Figure 4 is a transverse section, taken on the line 4—4 of Figure 2.

Figure 5 is a transverse section, taken on the line 5—5 of Figure 2.

Figure 6 is a transverse section, taken on the line 6—6 of Figure 2.

Referring to the drawings, the numeral 10 designates generally a removable box cap or cover, constructed according to an embodiment of this invention, for cardboard boxes containing cereal, baking powder, soap and other household material, the cover 10 being engageable on the cardboard box after the top has been removed therefrom. As many cardboard boxes, as the cardboard box 11, currently in use are formed with advertising media on the top wall thereof to be

severed from the box and returned to the manufacturer as a premium or the like, the box cap 10 is formed for engagement over the upper open end of the box 11 after the top wall has been removed therefrom.

The box cap 10 is formed with a horizontal top wall 12 having a material discharge opening 14 at one end thereof. By forming the opening 14 adjacent one end of the top wall 12, a substantial rim or peripheral edge is provided about the aperture or opening 14 for engagement over the extreme upper edges of the side and end walls of the container or box 11. The rim or edge 15 is disposed in the same horizontal plane as the major portion of the top wall 12 and a U-shaped guide channel or guide member 16 is fixed on the edge 15 about the opening 14. The channel 16 is substantially L-shaped in configuration, having a vertically extending arm 17 and a horizontally extending arm 18, spaced upwardly over the plane of the upper surface 10, for receiving thereunder the slidable closure member or door 19. The guide channel 16 is secured to the rim or edge 15, transversely thereof at one end of the top wall 10 and extends partway along the length of the side edges of the top wall 12, as clearly shown in Figures 1 and 2 of the drawings. The transverse portion of the guide channel 16 including the vertical arm 17 and the horizontal arm 18 are continued about the side edges of the opening 14 and the guide channel is open on the opposite end, from the transverse portion at one end of the wall 12 for slidably receiving thereunder the cover or door 19.

The door 19 is slidably engaged under the side channel member 16 and slidable over the major portion of the top wall 12 adjacent the guide channel terminal ends. An upwardly extending lug 20 is fixed to or formed integral with one end of the door 19 forming a handle or finger grip to effect the sliding movement of the door and an upwardly extending stop means or element 21 is fixed on the top wall 12, adjacent the end opposite from the opening 14 for limiting the sliding movement of the door 20 to the open position. The upwardly extending arm 17 of the transverse guide member 16, at the other end of the top wall 12 constitutes another stop element for limiting the sliding movement of the door 19 to the closed position, the horizontal bar 18 of the transverse guide channel 16 overlying the extreme end of the door 19 in its aperture closing position, as clearly shown in Figures 1 and 3 of the drawings.

A depending outer wall 24 is fixed to or formed integral with one end of the top wall 12 and a similar depending end wall 25 is fixed to the other end of the top wall. The outer walls 24 and 25 are connected together by longitudinally extending outer side walls 26 and 27. The top wall 12, end walls 24 and 25, and side walls 26

and 27 form a first casing having one end closed and the other end open. The outer end and side walls are adapted to be engaged in sliding engagement with the outer surface of the side and end walls of the cardboard container 11, as clearly shown in Figure 3 of the drawings.

An inner end wall 28 is fixed to or formed integral with the top wall 12, adjacent one end thereof, spaced inwardly from the outer end wall 24 and a similar end wall 29 is fixed to the opposite end of the top wall 12 inwardly of the outer end wall 25. The inner end walls 28 and 29 are connected together by longitudinally extending side walls 30 and 31 which depend from the top wall 12 and are spaced inwardly from the respective outer side walls 26 and 27. The end walls 28 and 29 and side walls 30 and 31 form a second casing having both ends open. The side and end walls of the box or container 11 are adapted to be telescopically received in the space between the inner and outer walls of the cap 10, as clearly shown in Figure 3 of the drawings.

For securely clamping the cardboard walls of the box 11 within the cap 10, inwardly extending, resilient, tangs or clamping elements 32 are struck inwardly from the outer side walls 26 and 27, spaced apart along the length thereof. In the normal position of the clamping elements or tangs 32, the upper edges of the tangs are biased into clamping engagement with the inner side walls 30 and 31, as clearly shown in Figure 4 of the drawings. When the side walls of the cardboard box 11 are received between the inner and outer walls of the cap 10, the inwardly biased tangs 32 will bear against the outer surface of the cardboard walls of the box 11 for pressing the walls of the box into clamping engagement with the inner walls of the cap 10.

For reinforcing the inner side walls 30 and 31 against the tension of the spring pressed clamping elements 32, a triangular bracing web 34 is fixed between the lower surface of the top wall 12 and the inside surface of the inner wall 30, intermediate the length thereof. A similar triangular reinforcing web 35 is fixed on the other side of the top wall 12, depending therefrom and in engagement with the inside surface of the other inner side wall 31, as clearly shown in Figure 5 of the drawings. The reinforcing webs 34 and 35 stabilize the inner side walls 30 and 31 when the side walls of the container 11 are pressed inwardly against the outer surface of the inner side walls 30 and 31 by the spring pressed clamping elements 32.

In the use and operation of the removable box cap 10, when the top wall has been removed from the cardboard box 11, the box cap 10 is slidably engaged on the box 11 by the telescopic engagement of the side and end walls of the box 11 between the inner and outer side and end walls of the cap 10. The clamping elements 32, of the outer side walls 26 and 27 clampingly engage the side walls of the cardboard box against the inner walls 30 and 31 of the cap 10. The closure member 20 will normally be in its closed position, as clearly shown in Figure 3 of the drawings, and for dispensing the material from the container or box 11 the closure member 20 may be slidably moved out of engagement with the transverse guide channel 16 and outwardly through the longitudinally extending side guide channels 16 for engaging the other end of the door 19 with the stop element 21, whereupon the opening 14 is opened for dispensing the material from the container 11. With the closure mem-

ber 20 in its closed position, the material within the box 11 is tightly or sealingly contained within the box 11 so that the material is held free from the deteriorating effects of moisture, dirt, insects or other material which is normally excluded from the contents of such containers.

I do not mean to confine myself to the exact details of construction herein disclosed, but claim all variations falling within the purview of the appended claims.

What is claimed is:

1. A removable box cap for an open topped box comprising a first casing closed at one end and open at the other end, the casing being adapted to be arranged so that its open end embraces the open topped box and is supported on the open topped box by its closed end thereof, a second casing open at both ends positioned within said first casing and having one of its open ends dependingly secured to the under surface of the closed end of said first casing, said second casing being spaced from said first casing to thereby form a space therebetween for receiving the portion of the wall of said box adjacent its open top, the closed end in said first casing being provided with a longitudinally extending opening adjacent one end thereof, a closure member arranged over said opening in said closed end and mounted on said closed end for sliding movement toward and away from said opening, and a plurality of resilient tongs projecting inwardly from said first casing intermediate its closed and open ends and engageable with the portion of the wall of said box when the latter is positioned within the space intermediate said first and second casings.

2. A removable box cap for an open topped box comprising a first casing closed at one end and open at the other end, the casing being adapted to be arranged so that its open end embraces the open topped box and is supported on the open topped box by its closed end thereof, a second casing open at both ends positioned within said first casing and having one of its open ends dependingly secured to the under surface of the closed end of said first casing, said second casing being spaced from said first casing to thereby form a space therebetween for receiving the portion of the wall of said box adjacent its open top, the closed end in said first casing being provided with a longitudinally extending opening adjacent one end thereof, a closure member arranged over said opening in said closed end and mounted on said closed end for sliding movement toward and away from said opening, and a plurality of resilient tongs projecting inwardly from said first casing intermediate its closed and open ends and engageable with the portion of the wall of said box when the latter is positioned within the space intermediate said first and second casings.
